UNITED STATES PATENT OFFICE.

CHARLES D. JENNEY, OF DETROIT, MICHIGAN.

LIQUID-VOLUME INDICATOR.

Application filed August 15, 1919. Serial No. 317,772.

To all whom it may concern:

Be it known that I, CHARLES D. JENNEY, a citizen of the United States, residing at Detroit, in the county of Wayne and State 5 of Michigan, have invented certain new and useful Improvements in Liquid-Volume Indicators, of which the following is a specification.

This invention relates to liquid level indicators and has for an object to provide a device especially, though not exclusively, for use on the fuel tank of an automotive vehicle to indicate the height of the motive fuel in the tank and consequently the volume 10 of fuel in gallons or other standard measure.

A further object of the invention is to provide a device adapted to be employed upon tanks of substantially the usual and 20 ordinary type and embodying new and improved features of convenience of installation and use, as well as economy and reliability.

Referring to the accompanying drawing 25 which forms a part hereof and on which similar reference characters indicate similar parts,

Figure 1 is a transverse sectional view through a conventional tank and through 30 the cap of the indicator, showing some of the working parts in section;

Figure 2 is a plan view of the dial.

Figure 3 is a sectional view, the plane of 35 which is at right-angles to the plane of Figure 1 and taken on line 3—3 of Figure 1, being partly in section and partly in elevation;

Figure 4 is a top plan view of the nipple with the cap removed;

Figure 5 is a plan view of the plate supporting the mechanism on the nipple, and

Figure 6 is a detail sectional view on line 6—6 of Figure 1, showing the manner of attaching the float to the rotating parts.

The improved liquid volume indicator which forms the subject matter of this application is adapted to be attached to a tank 10 of substantially the usual and ordinary type, the size and form in no way limiting the present invention, notwithstanding the fact that the tank, as shown at Figure 1, is indicated as circular and intended as cylindrical.

At substantially the top of the tank, anywhere throughout its longitude, an opening 55 is formed, over which is secured a nipple 12.

The manner of securing the nipple to the tank forms no part of the present invention, but is here disclosed by way of a substantially annular flange 13 riveted to the cylinder by means of rivets 14. The formation of the nipple 12 is such that the top or upper surface stands at an inclination to the radius struck from the center of the tank. In other words, with the tank located with the indicator at the top, the surface of the indicator will be inclined to a horizontal. This is desirable, especially for use in fuel tanks carried at the rear of a motor vehicle, for the reason that sight of the indicator from directly, or approximately, above is often obscured by the body of the vehicle as well as by extra tires or other accessories or impediments carried upon the vehicle.

The nipple 12 is provided in its upper surface with an opening 14' of such size and shape as to permit the insertion therethrough of the apparatus forming the structure of the operating mechanism. The shape of the opening 14', while shown at Figure 4 in a preferred form, is immaterial to the present invention. Upon its upper surface also the nipple is provided with an annular rabbet 15 into which is snugly fitted the plate 16. 80 To the plate 16 is secured a bar 17 in any approved manner, as by the rivets 18, and an ear 19 is secured to the plate 16 in any approved manner, as by rivets 20, the ear 19 being adjacent the opening 21 and spaced 85 from the bar 17.

Between the bar 17 and the ear 19 a sleeve 22 is journaled upon a pintle 23, which said pintle 23 is inserted through registering openings in the ear 19 and the bar 17 and is secured in any approved manner, as by forming a shoulder 24 thereon abutting the bar 17 and applying a lock-nut 25 as indicated more particularly at Figure 3.

Upon the sleeve 22 a graduated cylinder 100 26 is mounted by means of abutting against a shoulder 27 and the use of a spring washer or spider 28 and nut 29 by which tension can be exerted upon the graduated cylinder to permit of a manual turning of the same 105 when desired relative to the sleeve 22, but to normally hold such cylinder in position to travel with the sleeve. An arc of the cylinder 26 extends through the opening 21 and extends adjacent the disc 30 spaced from the disc 14 by a gasket 31. Over this disc 30 a glass plate 32 is employed preferably spaced

from the gasket 31 by a gasket 33 and with a gasket 34 interposed between such glass plate 32 and the inturned flange 35 of the screw cap 36. It will be obvious that by 5 tightening the screw cap 36 upon the nipple 12 all of the several members 15, 30 and 32 with their accompanying gaskets will be clamped firmly upon the nipple 12 whereby the bar 17 will assume an angular position 10 relative to a radius struck from the center of the tank to the fastened end of the bar 17 as indicated more particularly at Figure 1.

The bar 17 extends downwardly within 15 the tank 10 to a point somewhat below the center and is provided upon its lower extremity with a sprocket wheel 37. The sprocket 37 is mounted upon the bar 17 in any approved manner, as by striking up a 20 hub 38 and journalling upon the pintle 39 which is secured to the arm by the lock-nut 40. The sprocket 37 is connected with the sleeve 22 by means of a sprocket 41 rigidly secured upon such sleeve 22 with a sprocket 25 chain 42 or other flexible connecting means extending between the sprockets 37 and 41.

It is desirable to employ sprockets and sprocket chains, although it is to be understood that the present invention is to be in 30 no way limited to the type shown or any sprocket chain and is adapted to employ any form of coupling found desirable. It is also found desirable to insert within the length of the sprocket chain 42 a spring 43 35 for exerting the requisite tension to take up slack and by reason of the intervals between the sprockets 37 and 41 the spring 43 may be inserted without in any way interfering with the functioning of the sprocket chains. 40 Also for economy a single wire 44 may be inserted in the sprocket chain opposite spring 43 which by reason of the interval between the sprockets interferes not at all with the operation. It is obvious therefore that 45 as the sprocket 37 rotates, the cylinder 26 carrying the graduations, as indicated at Figure 2, will be rotated. To the sprocket 37 a float 45 is secured by means of an arm 46. The manner of connecting the arm 46 to 50 the sprocket 37 is immaterial to the present invention and the invention is in no way limited thereby, but an efficient and economical manner of attaching is by producing spaced openings through the sprocket 37 55 at points removed from the center, inserting the arm through one of said openings and returning through the other opening with the extremity upset as indicated at 47 and by bending down the intervening loop 48 60 into engagement with the surface of the sprocket, a rigid and efficient joint is produced.

As it is desirable that the graduations upon the cylinder 26 be as large as possible 65 to facilitate reading thereof, it is desirable

that the cylinder 26 makes substantially a complete rotation in registering extremes of liquid level. As indicated at Figure 1 the float 45 can oscillate in an arc considerably less than 180°, depending upon the structure. 70 The structure as disclosed at Figure 1 will permit an oscillation of approximately 120°. It is desirable, therefore, to gear up the cylinder 26 so that it shall make substantially a complete revolution to the movement of the sprocket 47 through an arc of 120°. For this purpose the sprocket 37 is made larger than the sprocket 41 sufficiently to insure a 75 complete rotation of the cylinder 26 with each complete oscillation of the sprocket 37. 80

It is also desirable that the indicator not only shall show the graduations as widely spaced as convenient, but that means shall be employed to warn the user of the approach to depletion of the fuel without necessitating the reading of the exact graduations upon the cylinder. For this purpose a portion of the cylinder is produced in a highly contrasting color as for instance, red, as indicated at Figure 2, to come into sight at the opening in the disc 30 when the fuel in the tank has reached a pre-determined danger line. As indicated at Figure 1, the red or danger section of the disc extends nearly to the numeral 2. This red section of the cylinder will come into view before it reaches the indices 49 so that when the fuel in the tank approaches depletion the red section of the cylinder will come into view and irrespective of the reading of the index prepared for that purpose, warning will be given of the dangerous level of the fuel. For reading during times of low visibility, it has been found that the cylinder having 95 a white background and black characters with a black surrounding field provided by the disc 30, is the most desirable combination and when a red section is provided upon the cylinder for warning, the combination is such a combination as will best serve the 100 purpose of indicating the contents of the fuel tank, for the greatest number of purposes and for the greatest number of times. 105

Having thus fully described my said invention, what I claim as new and desire to 115 secure by Letters Patent, is:

1. A liquid volume indicator comprising a tank of circular cross section, said tank provided with a nipple secured thereto, a graduated cylinder mounted on a bearing 120 carried by said nipple, a toothed wheel fixed to said bearing, a rigid arm extending from the nipple to the interior of the tank, said arm carrying at its inner end a toothed wheel to which is rigidly fastened an arm 125 provided at its extremity with a float, and a chain connection between the two said toothed wheels, substantially as set forth.

2. A liquid volume indicator comprising a tank of circular cross section upon which 130

is mounted a nipple, said nipple provided with a bearing upon which are fixedly mounted a toothed wheel and a graduated cylinder, said cylinder being provided with means whereby it may be manually adjusted with respect to its bearing, a rigid arm carried by said nipple and provided at its lower extremity with a loosely mounted toothed wheel, an arm rigidly mounted on said wheel and provided with a float rigidly secured to the extremity of the arm, and a chain connecting the two aforesaid toothed wheels, substantially as described and for the purpose set forth.

13 3. A liquid volume indicator comprising a tank, a nipple secured thereto, a shaft journaled in said nipple, a sprocket wheel mounted on said shaft, a graduated cylinder mounted on said shaft, an arm secured to the 20 nipple, a sprocket wheel mounted on the arm, a float connected to move with the sprocket wheel, and a chain connecting the two aforesaid sprocket wheels, substantially as set forth.

25 4. A liquid volume indicator comprising a tank, a nipple secured thereto, a shaft journaled in said nipple, a sprocket wheel mounted on said shaft, a graduated cylinder mounted on said shaft, an arm secured to the 30 nipple, a sprocket wheel mounted on the arm, a float connected to move with the sprocket wheel, and a chain connecting the two aforesaid sprocket wheels, said chain including an interposed section of a helical 35 spring, substantially as set forth and for the purpose thereof.

5. A liquid volume indicator comprising a tank, a support, a wheel pivotally mounted adjacent each end thereof, driving connections between said wheels, a float connected to move with the lower wheel, an indicating drum mounted coaxially with the upper wheel and rotatable therewith and a nipple secured to the tank and supporting the 45 aforesaid parts said nipple having a transparent portion permitting inspection of the indicating surface, as set forth.

6. A liquid volume indicator comprising a support, a wheel at each end thereof, driving connections between said wheels, a float 50 connected to move with the lower wheel, indicating means mounted coaxially with the upper wheel, and a slip connection between the indicating means and the second wheel, substantially as set forth.

55 7. A liquid volume indicator comprising a support, upper and lower sprockets thereon, a sprocket chain connecting them, a resilient connection interposed between two sections of the chain, a float connected to move with the lower sprocket, and indicating means driven by the upper sprocket, substantially as set forth.

8. A liquid volume indicator comprising a support, upper and lower sprockets thereon, a sprocket chain connecting them, a wire 60 interposed between two sections of the chain, a float connected to move with the lower sprocket, and indicating means driven by the upper sprocket, substantially as set forth.

65 9. A liquid volume indicator comprising a support, upper and lower sprockets thereon, a float connected to move with the lower sprocket, indicating means driven by the upper sprocket, a length of sprocket chain 70 engaging each sprocket, a spring connecting said lengths at one side, and a wire connecting them at the other, substantially as set forth.

75 10. A liquid volume indicator comprising a support, a wheel pivotally mounted adjacent each end thereof, flexible driving connections between said wheels, a float connected to move with the lower wheel, and an indicating drum rotated by said wheels, 80 substantially as set forth.

85 In witness whereof, I have hereunto set my hand and seal at Detroit Michigan, this 12th day of August, A. D. nineteen hundred and nineteen.
